UNITED STATES PATENT OFFICE.

JAMES VALENTINE ELLIS, OF LONDON, ENGLAND.

APPARATUS FOR TREATMENT OF STEEL INGOTS.

Application filed April 12, 1926, Serial No. 101,387, and in Great Britain March 18, 1926.

This invention has reference to an improved apparatus for the elimination of piping and segregates from steel ingots.

In the production of steel ingots it is well known that in the cooling process the outside walls first solidify and form an envelope enclosing metal not yet solidified and in the central part of the ingot a shrinkage cavity or pipe is formed by segregated gases, the walls of the pipe being covered with segregated impurities and impure metal and the upper ends of the finished ingots are finally "cropped" off in order to remove these impurities.

The amount of waste resulting in this cropping operation is considerable and the object of the present invention is to reduce this waste and to produce sound ingots in which the metal is consolidated throughout by side pressure on the ingot at the right period of the cooling operation so applied as to force the dross out of the body of the ingot so that the only cropping required is the removal of a mass containing the dross which is or can be caused by the said pressure to project from the top of the ingot.

According to the present invention the steel ingot prior to its core having solidified (which time is governed by the composition of the steel and the cross sectional area of the ingot) is placed in an appropriate container one or more sides of which is or are open to permit of a pressure plate or plates, carried by a suitable lever or levers actuated as by a hydraulic cylinder or cylinders, being so moved inwardly or towards the ingot as to press upon a surface or surfaces of the ingot to any required degree and over an area of any desired depth and width in such a way as to force the liquid steel still remaining in the core and which liquid contains the segregates, into the cavity which has already formed in the top of the ingot. If required the pressure can be maintained until the top surface cracks and the segregates are expelled thereby leaving a much greater weight of solid steel free from piping and segregates available for use.

It will be understood that any suitable mechanism may be employed for exerting the desired pressure in the manner above stated.

The accompanying illustrative drawing shows in longitudinal sectional elevation one example of apparatus suitable for exerting

the desired pressure on the ingots in the manner above stated.

The apparatus illustrated comprises two hydraulic cylinders 1 arranged in line with each other at opposite sides of a suitable holder 2 adapted to receive the base of an ingot 3. The rams 4 of said cylinders carry pins 5 that engage slots 6 in the lower ends of strong levers 7 the upper ends of which are pivoted at 8 to the side cheeks 9 of a suitable frame at points at a level above that of the top of an ingot 3 resting in said carrier. Intermediate of its ends each lever 7 is fitted with a removable pressure plate 10 adapted to press on the corresponding side of the ingot when the levers 7 are moved about their pivots 8 towards the ingot by outward movement of the rams 4 of the hydraulic cylinders 1.

After the desired squeezing pressure has been applied to the ingot the rams 4 are moved inwardly to bring the levers 7 into the dotted position indicated in order to release the pressure plates 10 from the ingot and the ingot is pushed up out of its carrier 2 by means of a pusher rod 11, extending through a central hole formed in the base of the carrier 2, operated by a hydraulic cylinder 12 located vertically below the carrier.

It will be understood that the sides of the ingot not subjected to the action of the pressure plates are supported by the side cheeks 9 of the supporting framework and if such side cheeks are arranged to receive between them ingots of greater cross section at the upper end than at the lower it is a simple matter to adapt the apparatus for treating ingots the top of which is narrower than the base by inserting wedge pieces of the required shape between the said side cheeks and the ingots.

As before stated, the construction of apparatus employed for carrying out the improved method of treating steel ingots may vary considerably without departure from the invention, and while it is preferred to employ the rams of hydraulic cylinders for exerting pressure through lever mechanism, the invention is not restricted to such an arrangement. An advantage of a lever arrangement such as described is that in the pressing operation the pressure plates can first make contact at their lower ends with the ingot and gradually squeeze the ingot

in an upward direction thereby ensuring that the segregates are forced upwardly out of the body of the ingot.

What I claim is:—

1. An ingot press, comprising a support for the ingot, a pressure member for bearing on one side of the ingot, a pivoted lever provided with a pressure member for bearing on the other side of the ingot, said lever having also a laterally projecting pin on its free end portion, and means for operating the said lever connected with it at a greater distance from its pivot than its pressure member, said means being provided with a slot which engages with the said pin.
2. An ingot press, comprising a support for the ingot provided with cheeks for positioning the ingot, a pressure member for

bearing on one side of the ingot, a lever 20 pivoted to the said cheeks and provided with a pressure member for bearing on the other side of the ingot, and means for operating the said lever connected with it at a greater 25 distance from its pivot than its pressure member.

3. An ingot press, comprising a support for the ingot having cheeks for positioning the ingot, pivoted levers having their upper end portions pivoted to the said cheeks and 30 provided with opposed pressure members at their upper parts for bearing on the upper portions of the ingot, and means for operating the said levers connected with their lower end portions below the bottom ends 35 of the said pressure members.

In testimony whereof I affix my signature.
JAMES VALENTINE ELLIS.
